UNITED STATES PATENT OFFICE.

ALFRED H. BROWN, OF FREEPORT, ILLINOIS.

COMBINED LATCH AND LOCK.

SPECIFICATION forming part of Letters Patent No. 356,027, dated January 11, 1887.

Application filed June 29, 1886. Serial No. 206,588. (Model.)

To all whom it may concern:

Be it known that I, ALFRED H. BROWN, a resident of Freeport, in the county of Stephenson and State of Illinois, have invented certain new and useful Improvements in a Combined Latch and Lock; and I do hereby declare the following to be a full, clear, and exact description of the invention, such as will enable others skilled in the art to which it pertains to make and use the same.

My invention is in locks of the class in which the key is inserted in the knob which actuates the catch. It comprehends a catch operated by either door-knob in the usual manner, a spring-catch that locks automatically when the door closes, and a lock of which the bolt can be moved from without only while the key is inserted, and in which pressure upon the end of the bolt cannot retract it. The lock may be instantly changed from one to another of these forms, and requires only the space occupied by an ordinary knob-catch without lock attachments. It involves a movable lug lying within the spindle and operated from without only by a key, and which may be thrown into engagement with the lock-case, preventing the turning of the spindle while permitting the sliding of the bolt by pressure upon the end thereof. This gives the action of a spring-lock. The lug may also be thrown out from the spindle still farther, when it engages not only the lock-case, but the catch or bolt itself. All motion of the bolt is then prevented, and the locking is absolute so long as the lug remains in this position. By moving a certain part upon the inner door-knob the lug may be thrown into either of its three positions, where it remains until said part is again moved, or until the key be inserted in the outer knob. The key may at all times, while inserted, withdraw the lug from engagement with both the lock-case and the bolt.

In the accompanying drawings, to which this specification refers, Figure 1 shows from above the relative position of the lock-case, knobs, key, and changing-piece, the door being indicated by dotted lines. Fig. 2 is a side elevation of the lock, one side plate being removed and the spindle cut in the plane of said plate when in position. Fig. 3 is an enlarged view of the spindle, both knobs being re-

moved. Fig. 4 is a longitudinal central section of the knob-spindle. Figs. 5 and 6 are detail views, explained in the following description.

In the drawings a mortise-lock is shown, although it is not essential that it be of this class. The relative position of lock-case, door, spindle, and knobs is the same as in ordinary knob-catches.

In Fig. 1, 1 is the door; 2, the lock-case. 3 and 4 are the knobs. 5 is the spindle, 8 the key, and 12 the catch-bolt. Within the case, and upon the spindle which passes through the case, is a short sleeve, 13, provided with lugs 13', which engage corresponding lugs upon the bifurcated inner end of the catch-bolt 12. A spring, 16, coiled about a stud, 15, acts in the usual manner to keep the bolt 12 thrown forward and projecting from the case, as shown. A lug, 9, Fig. 3, upon the body of the spindle engages constantly with the sleeve 13 by entering a slot, 18, Fig. 2, and insures the withdrawal of the bolt 12 whenever the spindle is rotated. The spindle is hollow, and within it a movable lug or latch, 10, Figs. 2, 3, 4, is mounted on a pivot, 24, Fig. 4. The outer edge of the free end of this lug lies in a slot, 11, in the spindle-shell, and normally flush with the outer surface of the spindle, as illustrated in Figs. 2, 3, 4; but it may be thrown out to the dotted lines 10', or to any intermediate position, by means of a spring-lever, 21, operated by a changing-piece, 7, Figs. 1, 3, 4.

Fig. 5 shows the lug and spring seen in the direction indicated by the arrow *a*, Fig. 4. The spring is pivotally inserted in the lug 10, near its free end, and is thus movable transversely to the plane of the lug. The other end of the spring is rounded, and fits loosely in a cup-like depression, 20, Figs. 4 and 6, in the end of the piece 7, which fits and rotates in the cylindrical spindle-cavity 17. Now, if the piece 7 be rotated, the outer end of the spring must move in a circle whose center is in the axis of the piece 7, and both lug and spring acting as a single lever fulcrumed at 24, the combination will, when the rotation is sufficient, take the position indicated by the dotted lines, Fig. 4. The spring thus far acts as a rigid bar, so far as its rotation about its fulcrum is concerned, the departure from its

100

original plane being allowed by its pivotal connection. If, however, the lug 10 be now forcibly depressed, it returns to its normal position, while the spring, flexed sufficiently to 5 permit its motion, restores it to its former position on the removal of the depressing force. The rotation of the changing-piece 7 is limited by a partial annular flange, 25, Figs. 4 and 6, whose edges strike a lug, 26, upon the interior 10 of the spindle, and its accidental movement from any position is prevented by a friction-pin, 19, pressed outward from the surface of the piece 7 by an underlying spring.

The spindle 5 and sleeve 13, Fig. 2, are retained in the same relative position with respect to each other by the lug 9 in the slot 18, and if the movable lug 10 be thrown outward slightly, as above described, when the parts are in the normal position of Fig. 2, it enters 15 a second slot, 32, in the sleeve 13, and also corresponding slots in the side plates, 2', of the lock-case, and the spindle cannot be rotated. Pressure upon the end of the bolt 12, however, will force it back, flexing the spring 16, and 20 sliding the bolt-lugs backward away from the sleeve-lugs 13', and we have a spring-lock automatically locking when the door closes. If the lug 10 be forced still farther out, it engages yet deeper with the lock-case, and also 25 with a slot, 14, in the bolt 12. The spindle cannot now be turned, nor can the bolt be forced back until the lug is again retracted. Whether the lug 10 shall be entirely within the spindle and the apparatus act simply as a 30 knob-catch, or slightly protruded to form a spring-lock, or fully thrown out engaging both case and bolt, depends on the position of the changing-piece 7 with reference to the spindle. In the other end of the spindle is a cylindrical 35 body fitting the spindle-cavity and having a cup-like depression similar to the depression 20 in the changing-piece 7, and serving a similar purpose. A bar, 27, whose rounded ends rest, respectively, in this depression and in a 40 bearing-socket, 34, in the lug 10, traverses a path similar to that of the spring 21, the transverse pin 33 in the spindle serving at times as a fulcrum, for as the end 35 of bar 27 is carried about by the rotation of the cylinder 45 23 the middle of the bar 27 must during a part of the revolution strike the middle portion of the pin 33, and if the other end of the bar be farther out than it is shown in the drawings, as must be the case if the lug 10 projects 50 from the spindle, it must be drawn back to the position shown, since the bar 27 is rigid; and this will be true even if the spring 21 must bend to permit such motion.

The rotation of the cylinder 23 is produced 55 by a flat key inserted in its outer extremity, and the arrangement of wards to prevent its turning when any other than the proper key is inserted may be any of the many, patented and unpatented, now in use without modifying any other parts.

If the outer edge, 30 31, of the lug 10 be made shorter, so as to fall entirely within the

lock-case cavity, the bolt will be prevented from moving by the entrance of the lug into the slot 14 alone; but in this case the slot 14 70 should be somewhat deeper than in the drawings.

What I claim as new, and desire to secure by Letters Patent, is—

1. In a combined latch and lock, the combination of a lock-case, a knob-spindle journaled in said case and having rotary but not longitudinal motion in its bearing, a catch-bolt operated by the rotation of the spindle, and a lug lying normally within the spindle and 80 adapted to be thrown outside the periphery thereof and into engagement with the case, whereby rotation of the spindle is prevented. 75

2. In a combined lock and latch, the combination of a lock-case, a knob-spindle journaled therein, a catch-bolt operated by the rotation of the spindle, and a lug lying normally wholly within the periphery of the spindle, but adapted to be projected outside of said periphery and to engage the catch-bolt, thereby preventing the rotation of the spindle and the longitudinal movement of the bolt. 85 90

3. In a latch and lock, the combination of a lock-case, a catch-bolt, a hollow knob-spindle, and a lug within said spindle adapted to be 95 thrown outward into engagement with either the lock-case or the lock-case and catch-bolt, whereby the simple knob-catch becomes a positive lock.

4. In a latch and lock, the combination of 100 a hollow knob-spindle, a catch-bolt operated thereby, a lug pivoted in a slot in said spindle, a spring-lever within said spindle attached at one end to said lug and having its other end carried in a circle by a hub revoluble in one 105 end of the spindle, whereby in the movement of the lever the lug-pivot acts as a fulcrum, and the lug is projected or retracted whenever the resistance to its movement is insufficient to flex the lever. 110

5. In a lock of the class specified, a hollow knob-spindle, a catch-bolt operated thereby, a lug projectible from said spindle near its middle, two hubs revoluble, respectively, on the ends of the spindle, two levers lying 115 within the spindle, each articulating at one end with said lug and being stepped at the other extremity in one of said hubs, near its circumference, and for the middle portion of each lever a fulcrum supported from the spindle, whereby the proper rotation of either hub may cause the corresponding lever to react against its fulcrum and project or retract the lug, substantially as and for the purpose set forth. 120

6. In a latch and lock, a lock-case, a hollow 125 knob-spindle, a catch-bolt operated thereby, a movable lug lying normally within said spindle and actuated from one side of the door by a revoluble changing-piece in the end of the spindle, and from the other side by a 130 key inserted in the other end of the spindle.

7. In a latch and lock, a catch-bolt, a hollow spindle adapted to operate said catch-bolt and provided with a movable lug adapted to en-

5 gage with the lock-case when protruded, a spring-lever connecting said lug with a revolute changing-piece in one end of the spindle, a rigid lever connecting said lug with a revolute key-actuated hub in the other end of the spindle, and a fulcrum-bearing for each of said levers, whereby the rotation of said changing-piece may cause the lug to project and engage the lock-case and bolt, and the rotation of the

hub may retract said lug, releasing said spindle to and bolt.

In testimony whereof I have signed this specification in the presence of two subscribing witnesses.
